UNITED STATES PATENT OFFICE.

EMMIT G. LATTA, OF SYRACUSE, NEW YORK, ASSIGNOR OF ONE-HALF TO HARVEY A. MOYER, OF SYRACUSE, NEW YORK.

RIBBON MECHANISM FOR TYPE-WRITING MACHINES.

933,186.

Specification of Letters Patent. Patented Sept. 7, 1909.

Application filed March 8, 1907. Serial No. 361,203.

To all whom it may concern:

Be it known that I, EMMIT G. LATTA, a citizen of the United States, residing at Syracuse, in the county of Onondaga and State of New York, have invented a new and useful Improvement in Ribbon Mechanisms for Type-Writing Machines, of which the following is a specification.

This invention relates more particularly to ribbon-operating mechanisms for type-writing machines of the visible writing kind in which the ribbon is vibrated to and from the printing position opposite to or over the printing point on the platen, so as to expose 10 the writing to view except when the ribbon is in the printing position.

The invention is directed to improvements in the means for guiding and vibrating the ribbon, for feeding it lengthwise, and for 20 reversing the direction of feed of the ribbon.

The invention is illustrated in connection with a front-strike machine but some of the features thereof are also applicable to other forms of typewriters and to other writing 25 or printing machines employing a ribbon.

One of the primary objects of the invention is to adapt a typewriting machine for the ready production of writing in different colors or kinds of ink. To this end, in the 30 preferred embodiment of the invention, the machine is equipped with a plurality of ribbons, preferably two, carrying inks of different colors or characteristics, which are arranged to pass the printing point one in front of the other or over the other, as regards the printing point, through vibrating 35 guides. The guides vibrate the ribbons together toward and from the printing position and are adapted to be adjusted or shifted to hold one ribbon in position for 40 use, and the other ribbon in an inoperative position. Means are also provided whereby either ribbon can be retained without vibration in the printing position when it is not 45 desired to expose the writing after each impression, or both ribbons can be held without vibration out of printing position when it is desired to use the machine for stencil cutting. Means are also provided whereby, if 50 preferred, a single ribbon carrying inks of different kinds or colors on separate fields or portions thereof, or carrying the same ink throughout, can be used instead of the two ribbons, and adjusted to place one or the 55 other portion thereof in position for use,

whether the ribbon be vibrated toward and from the printing point or retained in printing position.

Other objects of the invention are to furnish the machine with a ribbon shift key 60 adapted by successive like movements thereof to shift the ribbons to first place one and then the other in position for use, or, in the case of a single ribbon, to first place one and then the other portion thereof in position 65 for use; also to employ a separate pair of spools for each ribbon, where a plurality of ribbons are used, with a common driving and reversing mechanism therefor; also to provide differential drive gearing for the 70 ribbons whereby the tension on the ribbons will be equalized; also to provide drive and reversing mechanisms of simple, light running and durable construction; also to provide mechanism by which the movement of 75 the ribbon is reversed automatically by the carriage driving power and without undue strain on the ribbon; also to provide means for rendering both the ribbon vibrating and feeding mechanisms inactive; and to improve ribbon mechanisms in other respects 80 which will be hereinafter described and set forth in the claims.

In the accompanying drawings, consisting of five sheets: Figure 1 is a fragmentary 85 central longitudinal sectional elevation (full size) of a front-strike typewriting machine provided with ribbon mechanism embodying the invention. Fig. 2 is a front elevation, partly in section, thereof, in line 2—2, Fig. 1. 90 Fig. 3 is a plan view of the ribbon mechanism, the spools being removed, also showing portions of the top plate partly in section. Fig. 4 is a fragmentary plan view of the ribbon driving and reversing mechanism, 95 and horizontal section of the top plate, the spools and their ratchet wheels being removed and the top plate and pawl carrier being partly broken out to disclose the underlying parts. This view shows the reversing 100 lever buckled to throw the feed mechanism out of action. Figs. 5 and 6 are respectively a fragmentary longitudinal section and cross-section of the reversing lever and top plate, in lines 5—5 and 6—6, respectively, Fig. 3. Fig. 7 is a sectional elevation, on an enlarged scale, in line 7—7, 105 Fig. 2, of the spools and their operating mechanism. Fig. 8 is a detail horizontal sectional plan in line 8—8, Fig. 7. Fig. 9 is a 110

2
 fragmentary sectional elevation showing a single ribbon with its spool and vibrating guide. Fig. 10 is a sectional elevation, on an enlarged scale, of the ribbon vibrator and guides. Fig. 11 is a rear elevation thereof, partly in section. Figs. 12 and 13 are front elevations of the two ribbon guides detached. Figs. 14 and 15 are respectively a plan view and horizontal section, in line 15—15, Fig. 10, of the vibrator and guides. Figs. 16 and 17 are sectional elevations of the ribbon vibrating and shifting mechanism, the former showing the position of the parts when the ribbon is held covering the printing point, and the latter when the ribbons are held below the printing point for stencil cutting.

Like letters of reference refer to like parts in the several figures.

20 A represents a portion of the frame of a typewriting machine, of which a is the top plate, and a' a cross bar at the upper or near portion of the key-board.

25 B represents the platen, C, Fig. 1, the usual horizontally traveling carriage on which the platen is journaled, c the usual carriage driving spring drum, and D one of the type-bars which are pivoted to hangers on a segment or curved support d . In the machine illustrated, the type-bars are each actuated 30 by a finger key or key levers E, and auxiliary lever e' pivoted at one end, connected to the type-bar at the other end and having a curved or cam slot e' in which a stud e'' on the key lever engages. This slot is so shaped that 35 when the key lever is depressed the type-bar is started slowly and its motion is accelerated as it approaches the platen. As shown by the dotted line positions in Fig. 1, the type-bar is only moved about one-third of its travel by a depression of the key lever, one-half of its full movement, the remaining 40 two-thirds of the excursion of the type-bar being performed during the remaining half of the movement of the key-lever.

45 F represents the universal bar for the carriage escapement. The universal bar consists of a rock-shaft arranged in rear of the type-bar segment and having an arm f connected to the carriage escapement f' , and arms f'' , Figs. 1 and 2, which are operated by reciprocating actuators f^a through springs f^b . The actuators are arranged to be struck and moved rearwardly by the type-bars just before they strike the platen, or when they 50 are in the substantially upright position indicated by broken lines in Fig. 1. By this mechanism the carriage escapement is tripped suddenly just prior to the impact of the type-bars with the platen, and very 55 great speed of the machine is attainable. The type-bar action, the escapement and its actuating mechanism form no part of the invention and are thus briefly described to 60 show the relation between the same and the ribbon mechanism to be described later. Any

other suitable means for producing similar results could be employed.

The type-bars preferably carry upper and lower case type and the platen is normally retained in printing relation to one set of type and is shifted vertically into printing relation to the other type, for which purpose the carriage is preferably supported by a shift frame G which is pivoted at g at the upper rear portion of the main frame 70 and is raised and lowered by a pitman g' , Fig. 1, connected to an eccentric g^2 which is oscillated by a gear pinion g^3 thereon and a gear segment g^4 secured to a rock shaft g^5 provided at opposite ends with rock-arms g^6 80 which bear on and are rocked by pivoted shift levers g^7 located at opposite sides of the machine, see Figs. 1 and 2. The platen shifting also forms no part of the invention and any other suitable means for the purpose could be used.

H H' represent the two ink ribbons. The ribbons are connected to suitable spools operated to feed them lengthwise, as will be later described. Preferably each ribbon is 90 connected to a separate pair of spools, the spools h for one ribbon being arranged axially over those h' for the other ribbon. The ribbons pass one in front of the other, or face to face in front of or opposite to the 95 printing point, through suitable guides $I I'$ also arranged one in front of the other in front of the platen. These guides are normally supported so that one will hold the upper portion of one ribbon above the other 100 ribbon where the type can strike it and make the impressions without striking the lower ribbon, see Figs. 1 and 2. Both guides and ribbons are vibrated together and the guides can be shifted to thus hold either ribbon 105 uppermost.

The ribbon guides are preferably supported and vibrated by the following mechanism: K, Figs. 1, 2, 10, 11 and 14—17, represents an upright vibrator arranged in 110 front of the platen and secured at its lower end to an upright vibrator bar k which passes through and is adapted to reciprocate vertically in a guide slot k' in the type-bar segment between the two central hangers 115 and is connected at its lower end to a lever k^2 on a horizontal rock-shaft k^3 . Links k^4 pivoted at their rear ends to the top plate a and having connected front ends extending between and pivoted to rearwardly extending lugs on the vibrator, assist in supporting and guiding the vibrator. The rock-shaft 120 k^3 is supported in suitable bearings on the rock arms g^6 of the platen shifting mechanism, so that when the shift frame is raised 125 to shift the platen the rock shaft k^3 with the vibrator connected thereto will be bodily raised and place the ribbons in substantially the same relation to the platen when shifted as when in its lower position, shown in Fig. 130

1. The ribbon guides preferably have central pointers k^5 k^6 . The pointer of the higher guide normally stands opposite the lower edge of the scale k^7 on the carriage, to indicate the point for the next impression, and this pointer can be seen through an opening k^8 , Fig. 2, in the vibrator, while the other pointer will be too low to be seen through said opening k^8 .
- 10 L represents a universal bar or frame for operating the vibrator. It passes crosswise of the machine beneath the key levers E and has rearwardly-extending side arms l fixed to the vibrator rock-shaft k^9 . When any one of the type key-levers is depressed to actuate a type-bar it will depress the universal bar L, thereby rocking the vibrator rock shaft k^9 and lifting the vibrator so that the upper ribbon covers the printing point just in advance of the arrival of the type-bar at the platen. The vibrator is thus vibrated with the uniform speed of the key lever which is not so rapid as the accelerated motion of the type-bar or the carriage escapement universal bar F actuated by the type-bar. By thus using separate universal bars for the vibrator and carriage escapement, it is possible to use the quickest known escapement and vibrate the ribbon with a comparatively slow motion, thereby reducing wear on the vibrating mechanism and at the same time increase the speed of the escapement by relieving its universal bar of the extra work of vibrating the ribbon. A suitable spring l', Fig. 1, connecting the vibrator lever k^2 to an adjacent part of the frame A normally holds the universal bar L up against the key levers and returns it to this position and lowers the vibrator when the key lever is restored to the initial position.
- The ribbon guides I I', which are shown detached in Figs. 12 and 13, are placed face to face and held against the rear side of the vibrator K by guide lugs m at the sides of the vibrator, see Figs. 11 and 15. The guides can be shifted up or down in the vibrator to change the ribbons, and they will be held by friction in either position, the guides being preferably distorted in shape sufficiently to produce the necessary friction against the vibrator.
- The mechanism for shifting the guides is preferably constructed as follows: M, Figs. 1, 10, 11 and 15, represents a small disk which is seated in a depression in the rear side of the vibrator in front of the ribbon guides. The disk is pivoted by a screw m' to the vibrator and has two rearwardly projecting pins m^2 . Each ribbon guide, see Figs. 12 and 13, has a horizontal slot m^3 therein, the two slots being so located in the guides as to be at opposite sides of the center of said disk, and each guide has a large opening m^4 therein opposite to the slot m^3 in the other guide. Each pin m^2 passes through the large opening m^4 in one guide and the slot m^3 in the other guide, so that by turning the disk one guide will be moved up and the other down in the vibrator. m^5 represents a rod or strip of spring metal which passes vertically between the two central type-bar hangers, being guided by suitable brackets m^6 m^7 on the segment. This rod, which is laterally flexible, terminates at its upper end in a V-shaped fork m^8 , Fig. 11, which normally stands below the lower of the two pins on the disk M. The lower end of the fork rod m^5 is pivoted to the rear arm of a ribbon shift key or lever m^9 which is preferably located at the upper central part of the key-board and pivoted centrally to a bracket m^{10} secured to the cross bar a'. By depressing this key the fork-rod is raised and its fork engages the lower pin on the disk M, which, acting on the inclined side of the fork, deflects the rod until the pin bears in the crotch of the fork. In the further upward movement of the rod the fork partly turns the disk M, thereby moving one guide up and the other down, thus lowering the ribbon which was in position for use and raising the other ribbon in position for use, or, in other words, reversing the position of the ribbons. The fork swings outwardly with the ascending pin m^2 and passes the other pin without interference.
- When the ribbon shift lever m^9 is released and it and the fork-rod are retracted to the normal position by the spring m^{11} , Fig. 1, connected to the lever, the fork strikes the then lower pin m^2 and is held against assuming its central position, but with the first upward movement of the vibrator the pin clears the fork and allows it to spring back under the pin ready to act on this pin at the next upward movement of the fork-rod, to again reverse the ribbons. Normally the fork remains stationary below the pins of the disk and does not interfere with the vibration of the ribbons. Thus the relation of the ribbons can be changed and the new relation maintained by a single depression of the ribbon shift key, or the lower ribbon can be raised for one or more impressions and the other ribbon again restored by a second depression of the ribbon shift key. As before stated, the ribbon guides are held by friction in the adjusted positions in the vibrator. In shifting the ribbons the vibrator is therefore lifted to its limit before the disk turns to make the shift. The range of movement of the ribbon shifting device is great enough to effect the shift when the platen and vibrator are raised to the upper position for printing upper case characters. From this it will be seen that the ribbon guides with the ribbons are shifted in the vibrator by the simple depression of the ribbon shift key or lever, regardless of the position of the platen, and that like move-

ments of the same key always place a different ribbon in position for use, irrespective of which ribbon is used. The operator does not have to choose between two different parts, or decide which way a part should be moved to place the desired ribbon for use, but has only to depress the same key whenever a different ribbon is wanted, and this key is located near the upper central part 10 of the keyboard where it can be operated easily and quickly. The disk M is the only part of the shift mechanism that vibrates, so that the vibrator as a whole is light and works easily.

15 N, Fig. 9, represents a guide for a single ribbon adapted to be placed in the vibrator to replace the two guides H H'. This guide N is preferably longer than the other guides and made for a wider ribbon, its object being 20 to enable a single ribbon having two bands or fields of different colors or inks, one over the other, to be used instead of two ribbons, as described. An ordinary single color ribbon can also be used with this guide when different 25 colors or inks are not wanted. To substitute this guide for the two guides I I', the screw m' for the shifting disk M is removed and the guides raised in the vibrator until 30 the disk can be withdrawn through a hole L^o in the vibrator, when the guides can be pulled out of the upper end of the vibrator. The guide N has a slot n and a large opening n' which the pins of the disk M enter. By oscillating the disk M as before described, the pin in the slot n shifts the guide 35 alternately up and down by successive operations of the shift key. This guide is preferably made thick enough to fit snugly in the vibrator and be held by friction in either 40 of its positions. It preferably has a double pointer n² which stands above or below the scale, according to the position of the guide. When the single ribbon is used its upper band or portion normally occupies the 45 position of the upper of the two ribbons H H' and the actuation of the ribbon shift key places the upper portion of the ribbon opposite the printing point, so that when the vibrator is lifted through the universal bar 50 L the lower portion of the ribbon will be struck by the type-bars to make the impressions. Thus a single ribbon with different fields can be operated in the same manner as the two ribbons and by the same mechanism, by simply substituting the guide N in 55 the vibrator for the other two guides.

From Figs. 1 and 2 it will be seen that portions of the two ribbons overlap and only the upper portion of the upper ribbon 60 is exposed above the lower ribbon, this being so no matter which ribbon is the higher, the object being to limit the movement of the shifting device to the distance required to change the fields of the single ribbon, 65 and also to permit the ribbons to pass

through the guides with as little deflection from the plane of the spools as possible. Fig. 2 shows the ribbons in their normal position with the lower edge of the lower ribbon as far below the plane of the lower 70 spools as the upper edge of the upper ribbon is above the plane of the upper spools, when the upper ribbon covers the printing point with the platen in its upper or shifted position.

O, Figs. 1, 16 and 17, represents a sliding locking bar or device for the vibrator. This locking bar is arranged horizontally between the two central auxiliary levers, with its rear end supported and guided in a part of the bracket m' on the segment. A spring strip O' attached to the front end of the bar extends forwardly beneath the cross bar a' of the frame, having a rearwardly bent part or detent O² which bears on the top of said cross bar, and an upwardly-extending finger portion O³ for operating the locking bar. The detent O² is adapted to snap into either of three notches or depressions, 1, 2 and 3, in the top of the cross bar a' to hold the locking bar in either of three positions. The locking bar has a leg O⁴ which normally depends in front of the universal bar L, and a second leg O⁵, provided at its lower end with an anti-friction roller, which normally depends in front of an upwardly-extending arm or part p on the vibrator lever k². This vibrator lever is preferably loose on the rock shaft k³ and the hub of the lever has a shoulder which is normally held against a pin p² on the rock-shaft by a spring p³, see Fig. 3. This spring is stronger than the retracting spring l' for the vibrator lever so that the lever is caused to oscillate with the rock shaft when the universal bar is operated. If the operator does not care to see the printing after each impression and wants the higher speed of the machine with the lightest touch on the key levers, the universal bar L is depressed by one of the key levers and the locking bar O pushed rearwardly until its detent engages in the notch 2, as shown in Fig. 16. This places the depending leg O⁴ over the universal bar and holds the latter down out of reach of the key levers, thereby holding the vibrator up with one ribbon stationary opposite the printing point. As the ribbons pass forwardly from the guides, all but the last word or two of the writing 110 can be seen. When the vibrator is thus held the ribbon shift mechanism can be operated as described, to change the ribbons. When it is desired to use the machine for 115 stencil cutting, the locking bar O is pushed rearwardly until its detent engages the notch 3 in the cross bar a', as shown in Fig. 17, after the universal bar has been depressed, as before, which causes the depending leg O⁵ to engage the arm p of the 120

vibrator lever and swing the lever rearwardly and downwardly on the rock shaft h^3 (which is permitted by the spring p^3) to a position to hold the vibrator down with the ribbons below the printing point. In this adjustment of the locking bar its leg O^4 holds the universal bar down so that there is no tendency to lift the ribbon except as the carriage shift mechanism is operated and lifts the vibrator rock shaft. This movement of the rock-shaft cannot lift the ribbon to the printing position. The anti-friction roller on the leg O^5 of the rocking bar permits the arm p of the vibrator lever to move with less friction in shifting the carriage than if the roller were not used. When the parts are thus adjusted for stencil cutting, the finger portion O^3 of the locking bar stands under the ribbon shift lever and locks the latter against movement. The ribbon guides are restored for use by simply pulling the locking bar forward to the first or second notches in the cross bar a' , depending upon whether the ribbons are to be vibrated or retained stationary in printing position. In the vibrator mechanism described the ribbons vibrate together and do not chafe each other as in prior constructions, in which one ribbon vibrates independently of the other. The vibrator and guides are equally adapted for use with two ribbons wound face to face on a single pair of spools instead of on the separate pairs of spools shown.

The feed mechanism for the ribbons is preferably constructed as follows: The spools h for one ribbon H are arranged directly over the spools h' for the other ribbon H' on a single pair of upright shafts $R R'$ which are journaled at opposite sides of the front portion of the machine in bearings r depending from the top plate a . The top plate preferably has depressions r' forming seats for the spools. The spools are alike, see Fig. 7, and each preferably consists of opposite disks connected by a central hub r^2 which is surrounded by a sheet metal tube r^3 that serves to space the disks apart and form a core for the attachment of the ribbon. The adjacent ends of the spools on each shaft are preferably recessed centrally and each spool is provided in said recess with a bevel gear wheel r^4 formed by teeth on the hub of the spool. A small bevel pinion r^5 is arranged between the two spools and meshes with the bevel gear wheels r^4 of the spools. This pinion is journaled on a perforated plate r^6 , Figs. 7 and 8, which surrounds a sleeve r^7 loose on the spool shaft and has a projection or key engaging in a vertical keyway in said sleeve. This sleeve is formed with or attached to a ratchet wheel r^8 and is, together with the spools, held on the spool shaft by a screw or other device r^9 . This ratchet wheel is operated to rotate the spools,

its motion being transmitted to the spools through the bevel pinion and gear wheels which constitute a differential gearing which permits the spool having the least tension on its ribbon to overrun the other spool and thereby automatically equalize the tension on the two ribbons. The spools are thus preferably geared together to equalize their tension, but the ribbon feeding and reversing mechanism about to be described could be used with the spools connected in any other way or with a single spool on each shaft. A pawl carrier r^{10} is fixed to each spool shaft beneath the ratchet wheel and carries a pawl r^{11} which is pressed against the ratchet wheel by a suitable spring hidden in the pawl.

S' Figs. 1, 2 and 3, represent two horizontal feed levers pivoted between their ends on lugs depending from the top plate and having toothed segments s s' at their front ends which mesh with gear segments s^2 secured to the lower ends of the spool shafts, one in front of and the other in rear of the spool shafts. The rear ends of the feed levers are connected by a bar s^3 provided with a toothed rack projecting up through a slot s^4 in the top plate and meshing with a pinion s^5 which is secured to and rotates with the driving spring drum for the carriage. A roller s^6 journaled on a lug on the underside of the top plate holds the toothed rack in proper mesh with the pinion s^5 . The driving spring drum therefor turns both spool shafts whenever the carriage is moved, slowly turning the shafts in the opposite directions, as indicated by the arrows in Fig. 3, when the carriage moves step by step to the left in printing and reversing the motion of the shafts when the carriage is set back for a new line. Both feed pawls r^{11} oscillate back and forth with the spool shafts, one of them being held by its spring against its ratchet wheel r^8 to turn said wheel and the adjacent spools, while the other pawl is held away from its ratchet wheel so as to have no effect thereon, by a reversing lever $T T'$ which is arranged horizontally beneath and pivoted centrally to the front portion of the top plate. The lever has loops t^1 t^2 at opposite ends surrounding the spool shafts above the ratchet wheels.

In the position of the lever shown in Fig. 3, the circular portion of the loop t^1 is concentric with the left-hand spool shaft and engages an upright lug t^3 on the tail of the adjacent feed pawl and holds this pawl away from the ratchet wheel, while the corresponding part of the other loop t^2 is located far enough to the rear not to engage the lug t^3 on the adjacent feed pawl. In this position of the lever, therefore, the right-hand ratchet wheel and spools are rotated to wind the ribbon thereon, and the other ratchet wheel and spools are freed so that the ribbons will unwind therefrom. Dogs t^4 piv-

oted on the looped ends of the reverse lever are employed for holding the ratchet wheels from backward movement in the return movements of the driving pawls r^{11} . Spring t^5 , Figs. 3 and 4, press the holding dogs toward the ratchet wheels. Each dog has an upright lug t^6 and the loop of the reverse lever at the unwinding spools bears against this lug and holds the dog away from its ratchet wheel, as shown at the left in Fig. 3, so as not to interfere with the free movement of this ratchet wheel. To reverse the direction of feed of the ribbons it is only necessary to shove the forward end of the shift lever (the left end in Fig. 3) to the rear, whereby the left-hand feed pawl and dog are freed and allowed to engage their ratchet wheel, while the right-hand feed pawl and dog are held by the right-hand loop out of operative position. The shift lever is preferably provided near opposite ends with depending finger pieces t^7 for shifting it, and also with inclined depressions t^8 below holding screws t^9 , Figs. 3 and 4, depending from the top plate. The shift lever is of spring temper and when moved to either position, the conical or rounded end of one of the holding screws t^9 will snap into the adjacent depression t^8 in the lever and hold it stationary. The feed of the ribbons may be reversed manually by these means without additional parts, but automatic reversing mechanism is preferably employed which will be presently described. The reverse lever preferably consists of the two parts $T T'$ which are pivotally connected by the pivot t for the lever but are normally held rigid with each other by a claw t^{10} at the inner end of each lever-part which snaps into a V-shaped depression or notch t^{11} in the other lever-part, see Figs. 3 and 5. The lever thus normally acts as a single-piece rigid lever, and so far as the above-described reversing action is concerned, it could be made in a single-piece. With the two-part lever, however, the operator can hold one part stationary by its finger piece t^7 and pull the other part forward by its finger piece t^7 , thereby disengaging the claws t^{10} from the depressions t^{11} , whereby the lever will be buckled and both looped ends remain forward in position to prevent the feeding action of both pawls r^{11} . Thus the feed of the ribbons in either direction can be stopped and the machine relieved of this work when it is to be used in stencil cutting. The ribbon feed is restored by simply shoving one of the parts of the reverse lever forward until the two parts interlock. As before explained, the universal bar L and ribbon vibrator can also be thrown out of action for stencil cutting to relieve the key levers of the work of actuating the vibrator. The efficiency of the type mechanism can therefore be materially increased, which is desirable. The described ribbon feed mechanism is inexpensive, posi-

tive and direct in action, and causes less friction than the usual trains of bevel gears generally employed for the purpose. The feed and reversing mechanism is equally adapted for use with a single ribbon and 70 single pair of spools. In the case of a single ribbon, the spools $h h'$ together with the interposed bevel pinions r^5 are removed from the sleeves r^7 and the single spools slipped on the sleeves, the spools having keys to engage 75 the key ways in the sleeves, see Fig. 9.

The automatic ribbon reversing mechanism is preferably constructed as follows: U U', Figs. 1-4, represent ribbons guide levers having upright arms arranged adjacent to the spools for properly leading the ribbons to the latter. These upright arms preferably have slots $u u'$, Fig. 1, for the two ribbons $H H'$, one of which slots is above and preferably in rear of the other 80 to hold the overlapping portions of the ribbons from contact. The guides also have a third slot u^2 for a single ribbon, when such is used. The guide levers have horizontal portions pivoted at u^3 on the looped ends 85 of the reverse lever $T T'$, and these portions have rigid reversing pawls u^4 , the ends of which extend down and are adapted to engage with ratchet teeth on the edges of the feed pawl carriers r^{10} , which are of segmental shape, and arms u^5 to which the actuating springs t^5 for the holding dogs t^4 are attached. The tension on the ribbons tends to swing the guide levers and throw the reversing pawls u^4 against the toothed pawl carriers, but the swing of the holding dogs t^4 is limited by the engagement thereof with the ratchet wheels, or of their lugs t^6 with the reversing lever, and the dog springs t^5 are strong enough to hold the reversing 95 pawls away from the pawl carriers r^{10} except under the stronger pull on the ribbons when unwound from one set of spools. The one spring t^5 controls both the reversing 100 pawl and holding dog. When the ribbons are exhausted from the spools at one end, the slight increase in tension on the ribbons acts to swing the guide lever at the winding spools and engage its reversing pawl u^4 with the toothed pawl carrier, whereupon the pawl carrier, which is positively moved by the carriage driving drum through the ratchet wheel r^8 , swings the guide lever forward; thereby swinging the reverse lever on its pivot and reversing the ribbon feed in 105 the same manner as when operating the reverse lever manually. This action is assisted by the action of the inclined depressions t^8 of the reverse lever on the holding screws t^9 . When the reverse lever is at rest, one of these screws bears in its depression, and the other screw on the flat top of the lever in rear of its depression; and when the lever is first moved, one screw moves up the inclined surface of the depression onto the 110 115 120 125 130

flat surface of the lever and the upper end of the other depression is brought beneath its screw whereupon the pressure of this inclined face on the screw, due to the spring 5 action of the lever, will swing the lever and complete the reversal of the feed. The screw resting on the depression holds the reverse lever stationary until the action is repeated. During the last part of the forward movement of the guide lever with the end of the reverse lever, on which it is pivoted, its arm u^5 will strike the wall of the spool seat in which it is located and throw the reverse pawl u^4 out of engagement with 10 its toothed pawl carrier. The rearward movement of the other end of the reverse lever will clear the other guide lever from the wall of the spool seat in which it is located, so that this guide lever will be ready 15 for the automatic reversing operation when the ribbons are fully wound on the spools above it. The reverse is started by the pull of the ribbon on its guide lever near the winding spools, but the actual work of shifting the reverse lever is performed by the carriage driving drum, so that but slight 20 extra strain is applied to the ribbons. The reverse is effected by the mechanism at the full spools, and there is therefore less strain 25 on the ribbons than in prior constructions in which the ribbon acting through the empty spools actuates the reverse. This is because the friction on the ribbons at the 30 vibrating guides I I' assists in holding the reverse pawl against its toothed pawl carrier at the full spools, when the reverse goes into action instead of acting as an additional obstruction, as when the reverse is 35 effected at the empty spools.

40 The parts of the ribbon driving and reversing mechanism adjacent to the spools are located in the spool seats directly beneath the spools, where they can be reached by simply removing the spools, while at the 45 same time they are effectually protected from dust. The walls of the spool seats are cut out, as shown at V in Figs. 3 and 4, to allow the reverse lever with the parts connected thereto to be readily placed in position.

50 The ribbon vibrating and shifting mechanism described is not restricted to use in connection with the feeding and reversing mechanism described, nor to a typewriting machine of the construction illustrated, and, on the other hand, the feeding and reversing mechanisms can be used with other ribbon vibrating and shifting mechanisms. The feeding and reversing mechanisms can 55 also be used in other forms of machines for operating a single ribbon or a plurality of ribbons operatively connected to a pair of drive shafts.

60 I claim as my invention:

65 1. The combination of a vibrating sup-

port, two guides for separate ribbons supported by and vibrating with said support, means coöperating with parts on said guides for shifting the guides to change the relation of the ribbons, and a third guide for a single ribbon constructed to be mounted in said support in place of said two guides and having means for coöperation with the same shifting means for shifting the single ribbon to different positions, substantially as 75 set forth.

2. The combination of a vibrating support, two guides for separate ribbons supported by and vibrating with said support and normally holding said ribbons in different planes with a portion of one ribbon in advance of the other with respect to the printing point, a third guide for a single ribbon constructed to be mounted in said support in place of said two guides for the 80 separate ribbons, and a single means constructed for coöperation with parts on each of said guides for shifting either of said two guides or said third guide to different positions on said vibrating support, substantially as 85 set forth.

3. The combination of a vibrating support, a ribbon guide supported by and vibrating with said support, a type-operating keyboard, and a finger key located at or near 95 said keyboard for changing the position of said guide on said support, substantially as set forth.

4. The combination of a vibrating support, guides for two ribbons supported by 100 and vibrating with said support, a guide for a single ribbon interchangeable with said guides for the two ribbons on the support, and a finger key and connections for changing the position of either of said guides on 105 the support, substantially as set forth.

5. The combination of a vibrating support, a ribbon guide adjustable to either of two positions on said support, and a manually operated part for shifting the guide 110 from one to the other of said positions and always acting when moved in the same way to shift the guide, substantially as set forth.

6. The combination of a vibrating support, a ribbon guide on said support and 115 vibrating therewith, and a finger key acting alternately when moved in the same way to move the ribbon guide in opposite directions on its support, substantially as set forth.

7. The combination of a vibrating support, a guide for a ribbon movable to either of two positions on the support, and means normally out of contact with the support or guide and acting when moved to change the relative position of said guide with said support, substantially as set forth.

8. The combination of a vibrating support, a ribbon guide adjustably secured thereto, a ribbon guide shifting device on said support, a finger key, and connections 130

between said key and said shifting device for operating said device to shift the ribbon guide on its support, substantially as set forth.

5. 9. The combination of a plurality of vibrating ribbon guides adjustably supported, and a shifting device for said guides which always acts when moved in the same direction to change the relative position of said 10 guides, substantially as set forth.

10. The combination of a vibrating support, a ribbon guide thereon and vibrating therewith, means for shifting the guide to different positions on said vibrating support 15 to cause the guide to vibrate with the support to and from different positions relative to the printing point, and means for holding said support to retain the guide stationary in one or another relation to the printing 20 point, substantially as set forth.

11. The combination of a vibrating support, a ribbon guide adjustably secured thereon for changing the position of the ribbon, means for normally vibrating the 25 support and guide to cover and uncover the printing point with the ribbon, and means for holding the guide with the ribbon over the printing point, substantially as set forth.

12. The combination of a vibrating support, a ribbon guide adjustably secured thereon, means for normally vibrating the support and guide to cover and uncover the printing point with the ribbon, means for holding the guide from vibration with the 35 ribbon over the printing point, and means for shifting the ribbon guide when so held, substantially as set forth.

13. The combination of a vibrating support, a ribbon guide adjustably secured thereto for changing the position of the ribbon on said support, means for normally vibrating the support to cover and uncover the printing point with the ribbon, and means for holding the guide with the ribbon 40 over the printing point, or at one side of the printing point as desired, substantially as set forth.

14. The combination of a vibrating support, a ribbon guide on the support, and a 50 shifting device and operating key for shifting said guide, said shifting device acting between the vibrations of the ribbon and being positioned for its next shifting action by the first vibration of the support after having shifted the guide, substantially as set forth.

15. The combination of a vibrating ribbon support, an actuating universal bar for the same, and a single movable part for rendering the universal bar inactive and retaining said support with the ribbon either covering or uncovering the printing point, substantially as set forth.

16. The combination of a vibrating support, ribbon guides for two ribbons arranged

on the support and each having a printing point indicator, and means for shifting the guides to expose one of the indicators and conceal the other one, substantially as set forth.

17. The combination of a vibrating support, guides for two ribbons arranged on said support to hold the edge of one ribbon in advance of the other, and spools for the ribbons arranged midway between the planes 75 of the extremes of movement of the vibrating ribbons, substantially as set forth.

18. The combination of a vibrating support, a ribbon guide thereon, an oscillatory shifting device which vibrates with and is 80 connected to said guide, and an operating device for said shifting device which is normally stationary and is movable to engage and oscillate said shifting device to shift said guide on said support, substantially as 85 set forth.

19. The combination of vibrating ribbon guides, an oscillatory device which vibrates with said guides and has parts engaging the guides for changing their relative position, 90 a normally stationary rod which is movable to engage and oscillate said device, and an operating key or part for said rod, substantially as set forth.

20. The combination of a vibrating support, ribbon guides shiftable on said support, a disk pivoted on said support and having pins engaging said guides, a normally stationary forked rod which is movable to engage said pins to oscillate said disk, and an 100 operating key for said rod, substantially as set forth.

21. In a typewriting machine, the combination of a ribbon vibrator, a universal bar operated by the finger keys for actuating said 105 vibrator, a horizontally sliding locking bar which in one position engages and holds said universal bar out of reach of the finger keys to retain the ribbon in printing position, and in another position holds said universal bar 110 and also holds said vibrator with the ribbon out of printing position, substantially as set forth.

22. In a typewriting machine, the combination of a ribbon vibrator, a universal bar 115 operated by the finger keys for actuating said vibrator, said universal bar having a yielding connection with said vibrator whereby the vibrator can be moved independently of the universal bar, and a locking device which 120 is movable to place said vibrator with the ribbon out of printing position and to hold said universal bar stationary, substantially as set forth.

23. In a typewriting machine, the combination of a plurality of ribbons, and drive mechanism for said ribbons including differential gearing for equalizing the tension on said ribbons, substantially as set forth.

24. In a typewriting machine, the combi- 130

- nation of spools for a plurality of ribbons, and differential gearing connecting said spools to equalize the tension on said ribbons, substantially as set forth.
- 5 25. The combination of a ribbon spool driving shaft, spools loosely mounted thereon, and differential gearing connecting the spools to the shaft, substantially as set forth.
26. A ribbon spool comprising a pair of centrally perforated end plates, a shouldered tubular hub riveted at one end to one end plate, and a spacing tube surrounding the hub between the end plates, substantially as set forth.
- 10 27. A ribbon spool comprising a pair of centrally perforated end plates, one of said plates having a central depression, a tubular hub having a head seated in the depression, and a spacing tube surrounding the hub between the end plates, said hub being riveted to the other end plate to secure the parts of the spool together, substantially as set forth.
- 20 28. In a typewriting machine, the combination of carriage driving means, a pinion driven thereby, a rack meshing with said pinion, a pair of centrally pivoted levers connected at one end to the rack to move therewith, and a pair of ribbon spools operatively connected to the other ends of said levers, substantially as set forth.
- 25 29. In a typewriting machine, the combination of a pinion driven by the carriage driving means, a rack meshing with the pinion, a pair of centrally pivoted levers connected at one end to the rack to move therewith, and gear connections between the other ends of the levers and the spools with means for alternately connecting and disconnecting the spools from the levers, substantially as set forth.
- 30 30. A ribbon driving mechanism comprising a pair of spool shafts, spools thereon, a pair of centrally pivoted levers operatively connected at one end to the spool shafts, a rack bar connected to the other ends of said levers to move the levers in unison, a rack on said bar, and a driven pinion meshing with said rack, substantially as set forth.
- 35 31. In a typewriting machine, a ribbon driving mechanism comprising a pair of rotary spools, a pair of centrally pivoted levers operatively connected at their front ends to the spools, carriage driving means, a pinion connected thereto, a rack bar meshing with the pinion and connected to the rear ends of said levers, and a roller acting to hold the rack in proper relation to the pinion, substantially as set forth.
- 40 32. In a typewriting machine, a ribbon driving mechanism comprising a pair of rotary spools, a pair of centrally pivoted levers operatively connected at one end to the carriage driving means to cause both levers to move at all times with the carriage, and means for alternately connecting and disconnecting the spools from the other ends of the levers, substantially as set forth.
- 45 33. In a typewriting machine, a ribbon driving mechanism comprising a pair of rotary spools, upright spool shafts journaled under said spools, operative connections between the spools and shafts located under the spools and above the journals for the shafts, and operative connections between the lower ends of the spool shafts and the carriage driving means, substantially as set forth.
- 50 34. In a typewriting machine, a ribbon driving mechanism comprising a pair of rotary spools, a pair of spool shafts supporting the spools, a pair of centrally pivoted levers operatively connecting the spool shafts to the carriage driving means whereby both spool shafts move at all times with the carriage, and means for connecting one shaft with its spool and disconnecting the other shaft and spool, substantially as set forth.
- 55 35. In a typewriting machine, a ribbon driving mechanism comprising a pinion driven by the carriage driving means, a rack meshing with said pinion, a pair of centrally pivoted levers connected at one end to the rack, a pair of spool shafts, gears connecting said shafts with the other ends of said levers, spools mounted on the shafts, ratchet and pawl connections between said spools and the shafts, and means for connecting and disconnecting said ratchet and pawl connections, substantially as set forth.
- 60 36. In a typewriting machine, a ribbon driving mechanism comprising a pair of spool shafts, spools thereon, power driven means for rotating the spools, clutch connections between said spool shafts and said power driven means, and a centrally pivoted lever extending from one of said clutch connections to the other and acting when rocked on its pivot to reverse the ribbon feed, substantially as set forth.
- 65 37. In a typewriting machine, a ribbon driving mechanism comprising a pair of spool shafts, spools thereon, means for driving the shafts, ratchet and pawl connections between the spools and shafts, and a centrally pivoted lever acting when rocked on its pivot to withdraw one pawl from its ratchet and permit the other pawl to engage the other ratchet, substantially as set forth.
- 70 38. In a typewriting machine, a ribbon driving mechanism comprising a pair of spools, means for driving the spools ratchet and pawl connections between the spools and power driven means, and a centrally pivoted lever having curved ends acting to hold one of the driving pawls out of contact with its ratchet and to release said pawl and withdraw the other pawl when the lever is rocked on its pivot, substantially as set forth.
- 75 39. In a typewriting machine, a ribbon driving mechanism comprising a pair of

- spools, driving means for the spools, connections between the spools and driving means, and a reverse lever consisting of two parts connected by a central pivot and normally held rigid with each other and acting when rocked on said pivot to disconnect one spool from the driving means and permit the movement of the other spool with the driving means, substantially as set forth.
40. In a typewriting machine, the combination of a top plate, a ribbon spool at each side of the top plate, driving means for turning said spools operatively connected to the spools, and a reverse lever centrally connected to the top plate and acting when moved to reverse the ribbon driving means, substantially as set forth.
41. In a typewriting machine, the combination of a top plate, a ribbon spool at each side of the top plate, ribbon driving mechanism consisting of spool shafts, and driving means therefor, operative connections between the spools and shafts, and, a reverse lever pivotally connected to the top plate and acting when rocked on its pivot to reverse the ribbon driving mechanism, substantially as set forth.
42. In a typewriting machine, the combination of a top plate, a ribbon spool at each side of the top plate, driving means for the spools, and a reverse lever centrally connected to the top plate and concealed thereby, substantially as set forth.
43. In a typewriting machine, the combination of a top plate, a ribbon spool at each side of the top plate, means for driving the spools, and a reverse lever centrally pivoted to the underside of the top plate and having a projecting handle at each side of its pivot by which the lever can be rocked to reverse the ribbon feed, substantially as set forth.
44. In a typewriting machine, a pair of ribbon spools, driving means for the spools, driving ratchet and pawl connections between the spools and driving means, dogs for engaging said ratchets for holding the spools against backward movement, and a single centrally pivoted lever located at the front portion of the machine for disconnecting both the driving pawl and holding dog from one spool and simultaneously restoring the driving pawl and holding dog for the other spool to operative position, substantially as set forth.
45. In a typewriting machine, a pair of spools, ratchets for said spools, power-driven pawls for driving the ratchets, reversing pawls whose positions are controlled by the ribbon but which are power-driven for disconnecting the driving pawls from the ratchets, and a connection between said driving pawls and controlled by said reversing pawls by which one of the driving pawls is moved to operative position and the other is removed from operative position, substantially as set forth.
46. In a typewriting machine, a pair of spools, power-operated driving means for said spools, parts driven by said power-driving means for reversing the feed of the spools, a reversing pawl adjacent to each of said parts and adapted to be moved into operative contact therewith by the tension of the ribbon, and a connection between said reversing pawls causing them to act alternately to reverse the ribbon feed, substantially as set forth.
47. In a typewriting machine, a pair of spools, power-driven means for rotating the spools, a toothed reversing device for each spool driven by said power-driven means, a pair of reversing pawls controlled by the ribbon to act on said toothed reversing devices, and a lever actuated by either of said reversing pawls to position the other reversing pawl in position to engage its toothed reversing device, substantially as set forth.
48. In a typewriting machine, a pair of shafts, a pair of ribbon spools, power-driven means for rotating said shafts, a ratchet and pawl connection between each spool and one shaft, a reversing pawl for engagement with a part connected to each shaft, and a reversing lever connecting said reversing pawls and pivotally supporting the same, substantially as set forth.
49. In a typewriting machine, a pair of shafts, a pair of ribbon spools, power-driven means for rotating said shafts, a ratchet and pawl connection between each spool and one shaft, a holding pawl to prevent backward movement of each ratchet, a reversing pawl for engagement with a part connected to each shaft, and a reversing lever supporting both the holding and reversing pawls, substantially as set forth.
50. In a typewriting machine, a pair of shafts, a pair of spools, power-driven means for rotating said shafts, a ratchet and pawl connection between each spool and one shaft, a holding pawl to prevent backward movement of each ratchet, a reversing pawl adjacent thereto, a spring connecting each holding pawl to the adjacent reversing pawl, and means for operating said reversing pawls, substantially as set forth.
51. In a typewriting machine, a pair of spools, power-driven means for rotating the spools, ratchet and pawl connections between the spools and said driven means, a pair of combined ribbon guides and reversing pawls thrown into action by increased tension on the ribbon, and connections between said pawls and said driven means for causing said power-driven means to reverse the feed of the ribbon, substantially as set forth.

52. In a typewriting machine, a pair of spools, power-driven means for rotating the spools, clutch connections between the spools and power-driven means, a pair of toothed parts and pawls for engaging said toothed parts to reverse the ribbon feed, and a stop for each pawl to hold it out of contact with said toothed part after having reversed the feed of the ribbon until after the other pawl 10 has acted, substantially as set forth.

53. In a typewriting machine, a pair of spools, power driven means for rotating the spools, independent clutch connections between each spool and said power driven means, and automatic means for reversing the feed of the ribbon by the power driven means, said automatic means being caused to act by the increased tension of the ribbon at the winding spool, substantially as set 20 forth.

54. In a typewriting machine, a pair of spools, power-driven means for rotating the spools, independent clutch connections between each spool and said power-driven means, a reverse lever centrally pivoted between the spools, and spring detents located at opposite sides of the lever pivot, and act-

ing alternately on the lever as it is rocked on its pivot, substantially as set forth.

55. In a typewriting machine, a pair of 30 ribbon spools, power driven means for rotating the spools, independent clutch connections between the spools and said power-driven means for positively driving either one of said spools, and means for disconnecting said power-driven means from both spools and causing both spools to remain idle, substantially as set forth.

56. In a typewriting machine, a pair of 40 ribbon spools, power driven means for rotating the spools, independent clutch connections between the spools and said driven means, means for vibrating the ribbon to and from the printing point, and means for rendering both the power-driven rotating 45 means and vibrating means inactive, substantially as set forth.

Witness my hand, this 1st day of March, 1907.
